UNITED STATES PATENT OFFICE.

WILLIAM STUBBLEBINE, OF BETHLEHEM, PENNSYLVANIA.

AIR-HEATING APPARATUS FOR FURNACES.

SPECIFICATION forming part of Letters Patent No. 573,799, dated December 22, 1896.

Application filed March 11, 1896. Serial No. 582,807. (No model.)

To all whom it may concern:

Be it known that I, WILLIAM STUBBLEBINE, a citizen of the United States, residing at Bethlehem, in the county of Northampton and State of Pennsylvania, have invented certain new and useful Improvements in Air-Heating Apparatus for Furnaces; and I do hereby declare the following to be a full, clear, and exact description of the invention, such as will enable others skilled in the art to which it appertains to make and use the same.

My invention relates to regenerative and reverberatory furnaces largely used in the manufacture of iron or steel, although the improvements are applicable to, and susceptible of use in connection with, blast-furnaces generally where it is desirable to heat the air before forcing the same into the grate-chamber or working chamber of the furnace. In the erection of the common metal-working furnaces it has been the general, although not the exclusive, custom to place the air-heating or regenerating appliances under the ground-line or in some part of the furnace which is not readily accessible for repairs and cleaning. This requires considerable tearing out of the furnace to have access to the air-heating appliances for repair and other purposes, thus involving time and expense. It is my purpose to provide a simple and comparatively inexpensive construction which is readily accessible for purposes of repairs and in which the air-blast may be heated to the proper temperature in an economical and expeditious manner.

In the preferred embodiment or construction of my air-heater I employ metallic base-plates which are protected from the action of heat by refractory or fireproof slabs or blocks, and into these metallic base-plates are secured the ends of metallic heating-pipes arranged to conduct the air-blast from the lower compartment to the upper hot-air compartment. Each metallic air-heating pipe is protected from the deteriorating influence of the high heat or temperature in the middle compartment by refractory tiles, which are placed over and around said metallic pipes or tubes so as to rest or be superimposed one on top of the other, and said tiles are coupled together by interlocking joints.

My invention further consists in the novel

combination and construction of parts, which will be hereinafter fully described and claimed.

55

To enable others to understand my invention, I have illustrated the same in the accompanying drawings, forming a part of this specification, and in which—

Figures 1, 2, and 3 are sectional views of an ordinary reverberatory furnace with my improved air-heater embodied therein, Fig. 1 being a horizontal section on the plane indicated by the dotted line 1 1 of Fig. 2; Fig. 2, a vertical longitudinal sectional view on the line 2 2 of Fig. 1, and Fig. 3 a vertical transverse sectional elevation on the line 3 3 of Fig. 1. Figs. 4, 5, and 6 are respectively a vertical longitudinal sectional elevation, a horizontal sectional plan, and a vertical transverse sectional elevation taken, respectively, on the planes indicated by the dotted lines 4 4, 5 5, and 6 6 through a regenerative furnace having my air-heating appliances embodied therein. Figs. 7 and 8 are respectively a perspective view and a sectional elevation through one of the air-heating pipes and the tiles for protecting the metallic pipe or tube. Figs. 9 and 10 are respectively a perspective and a sectional elevation of another form of the air-heating pipe and tiles therefor. Figs. 11 and 12 are detail perspective views of the tiles shown by Figs. 7, 8, 9, and 10, respectively.

Like letters of reference denote corresponding parts in all the figures of the drawings.

A designates the working chamber of an ordinary furnace.

B is the combustion or grate chamber, and C is the stack or uptake.

In the construction of the furnace to accommodate my improved air-heater for the blast from the blast pipe or pipes C' C' the rear or back wall D to the chamber A is constructed with a vertical air-heating chamber 95 or chambers E E.

In the embodiment of the invention in the reverberatory furnace shown by Figs. 1, 2, and 3 the air-heating chambers E E are divided by the uptake or stack C, thus forming 100 two chambers, which are situated on opposite sides of the stack or uptake, and these chambers E E communicate with the working chamber A through the medium of the

inlet openings or passages F F, which are formed in the walls d, that separate the chambers E E from the working chamber A. Said chambers E E also communicate with 5 the uptake or stack C by the flues or passages F' F', formed in the walls d' d' of the stack, and these outlet passages or flues F' F' are located some distance above the inlet passages or openings F F, whereby a part of 10 the heat from the working chamber A is caused to circulate around and through the chambers E E before it escapes from the chambers E E into the uptake or stack.

Each heating-chamber E E is divided into 15 the three compartments or subchambers e e' e² by means of the horizontal walls G G', one of which walls G is provided near the lower part of the chamber E below the intake-passage F, while the other wall G' is arranged 20 near the top of the chamber E and at a suitable distance above the outlet-passage F' from said chamber E. The middle compartment or subchamber e' is much deeper than either the upper or lower compartments or 25 subchambers e e², and through the deep middle compartment e' passes the series of air-heating pipes or tubes H H', which are protected by the refractory tiles I I' I², as will be hereinafter more fully described,

30 The division wall or floor G in each chamber E is composed or laid of fire-brick or refractory tiling in one, two, or three courses, and this fire-brick floor is laid on and supported in a suitable way within the chamber 35 E to leave the lower subcompartment e free and unobstructed for the passage of the air-blast to and through the heating-flues formed by the pipes and refractory tiles. The blast-pipes C' C' discharge into the subcompart- 40 ments e e of the chambers E E in a suitable way, or said pipes may discharge into boxes c, (shown by Fig. 2,) from which the blast is delivered to the series of tubes.

Below the wall or floor G in each chamber 45 E is secured one or more metallic base-plates J, which have threaded holes produced there-in, and in these holes of the metallic plate or plates J are screwed the lower threaded ends of the metallic heating-pipes H H', the lower 50 ends of which are open for the free and unobstructed passage of the air-blast to the pipes or tubes H H'. These pipes or tubes pass through the fire-brick floor G and through the deep middle compartment e' and through 55 openings in the upper division-wall or roof G', whereby the pipes take the blast of air from the lower compartment e, conduct the same through the middle compartment e', and deliver it to the upper compartment e², the 60 air-blast being heated by contact with the hot pipes or tubes. These pipes or tubes are made of metal to afford a good heating surface or medium for quickly heating the air-blast during its passage through the tubes or pipes, and 65 said tubes if left unprotected would rapidly deteriorate under the influence of the high temperature of the compartments e', which

communicate directly with the working chamber A through the inlet-passages F. To protect the metallic tubes against the action of 70 the heat, I provide the incasing tiles I I' I² for each tube. These tiles are made of fire-resisting refractory material, suitably molded and hardened before setting them around the metallic tube or pipe, and each tile, except 75 the bottom tile of the series, is provided at one end with a contracted nipple i, and at its other end with an internal groove or recess i', forming a seat to receive a nipple on an adjacent tile. After each metal tube or pipe 80 has been screwed into the metallic base-plate J the bottom tile I is slipped over the tube or pipe and its lower solid or ungrooved end is fitted in a groove or recess i², produced in top layer or course of the wall or floor G. The 85 next tile I' is placed over the tube so that the nipple i on the lower tile fits in the seat i' of the tile I', and the two tiles abut solidly or squarely together. The succeeding tiles are 90 then placed in position with the nipples fitting in the seats of adjoining tiles until the top tile I² is reached, whereupon the tile I² is adjusted to have its nipple i fit tightly in the roof or crown G' of the compartment e' of the chamber E. It will thus be seen that each 95 tube H or H' is thoroughly protected against the heat by the incasing stack or series of tiles, which are superimposed one on top of the other and are coupled together by interlocking joints. The interlocking ends of the 100 tiles may be united together by cement or in any other suitable way, if desired, as will be readily understood by those skilled in the art; but I do not deem it essential to fasten the tiles together, as the interlocking joints will hold 105 the tiles in place when they are stacked and properly adjusted in the heating-chamber.

The top wall or roof G' in each chamber E is supported by the walls of the chamber E in any suitable way, and this roof G' may consist of fire-brick or metal, or both, which may be let into the walls of the chamber E.

The heated air-blast from the series of pipes H H' is delivered into the chamber e', and it is conducted from thence to the working chamber A through the side flues K, which have ports k, that open into said working chamber, as shown by Figs. 1 and 2.

The operation of the furnace shown by Figs. 1, 2, and 3 is simple and readily understood 120 from the foregoing description, taken in connection with the drawings. When the furnace is in operation, a part of the heat from the working chamber A passes into the compartments e' through the inlet-passages F, 125 and the remaining heat from said chamber A escapes through the arched opening b into the stack C. The heat admitted to the compartments e' e' of the chambers E E circulates in contact with the tile-incased pipes or tubes H H' and heats the same to a temperature 130 proper for heating the air-blast, and the heat in the compartments e' e' escapes into the stack C through the upper outlet-passages F' F'. The

air-blast from the blast-pipes $c' c'$ is delivered to the subchambers $e e$ of the chambers E E, passes through the tile-protected pipes or tubes H H', is delivered into the upper chambers $e^2 e^2$, and thence passes through the flues and ports K k into the working chamber A.

In the embodiment of my invention in a regenerative gas-furnace (shown by Figs. 4, 5, and 6) the rear wall of the furnace is constructed with a single transverse air-heating chamber E, which extends the full width of the furnace, as shown by Fig. 5, and which is situated between the working chamber A and the stack or uptake C. This single transverse chamber E communicates with the working chamber by means of the two inlet-passages F F, produced in the wall d near the side walls of the furnace, (see Fig. 5,) and said chamber E is connected to the stack C by a single central outlet-passage F', that is arranged on a plane some distance above the inlet-passages F F, so that the heat from the working chamber is caused to sweep within or circulate through the chamber E before the heat escapes through the outlet-passage F' to the stack. This single transverse chamber E in the regenerative furnace is divided into the three compartments $e e' e^2$ by the two division-walls G G', or, as they may be termed, the "floor" G and the "roof" G', and the deep middle compartment e' of this chamber E connects by the passages F, F, and F' with the working chamber A and the stack C, respectively, as shown.

The floor G consists of two or more courses of fire-brick or tiles let into the walls d d' of the chamber E, and it rests on the intermediate pillars or arches d², erected in the lower subchamber e. To the lower side of this floor G are applied the metallic base-plates J, which receive the lower threaded ends of the metal pipes or tubes H H', that pass through the floor G, the compartment e' , and the roof G', and said pipes or tubes H H' are protected by the refractory tiles I I' I², constructed and arranged in the manner shown and described in connection with the reverberatory furnace illustrated by Figs. 1 to 3, inclusive.

The blast pipe or pipes C' C' discharge the air-blast into the lower chamber e below the bed of the working chamber A, and the blast passes through the tile-incased pipes H H' and into the upper compartment e^2 of the chamber E, the blast being heated during its passage through the pipes or tubes H H'.

The combustion or grate chamber B at the front of the furnace has a bridge-wall b between the grate and chamber A, and on the front of the furnace is the gas-supply pipe M, having the nipples m, which discharge into the combustion-chamber B. The roof N of the furnace is curved down or deflected over the combustion-chamber, as at n, and in this deflected part n of the furnace-roof are the air-inlet openings n'. In each side of the furnace are provided two longitudinal flues O O', and

across the front part of the roof N, above the deflected part n, is an air-chamber N', which delivers air to the openings n'. The two outside flues O O on the sides of the furnace connect at their rear ends with the upper compartments $e^2 e^2$ of the chamber E, and the front ends of said flues O O deliver the hot-air blast to the chamber N', from whence the air-blast passes through the ports n' into the upper part of the combustion-chamber B. The other side flues O' O' of the furnace connect with the upper compartments $e^2 e^2$ of the chamber E, and these flues O' O' (which lie within the flues O O) have ports or openings o², which extend inwardly from the flues and open into the chamber A through the side walls of the furnace. In these side flues O' O' are provided the valves or dampers P P', having suitable handles, which extend outside of the furnace, so that either of the valves may be operated to close the flues and shut off the air from passing either to the working chamber A or the combustion-chamber B.

In the application of the tubes or pipes H H' in the single transverse chamber E of the regenerative furnace shown by Figs. 4 to 6, inclusive, the tubes are arranged in sets, and one plate J is provided for each set of tubes. As shown by Fig. 6, a series of these plates J is provided, and a set of four tubes or pipes H H' is attached to each plate, although the number of tubes to each plate may be increased or diminished. The plates J and the sets of air tubes or pipes are arranged in series in the direction of the length and width of the chamber E, whereby a large number of air-heating tubes are compactly arranged within said transverse chamber to secure a large surface or area for heating the air-blast.

It will be observed that the metal base-plates, to which the tubes have their lower ends attached, are protected by the refractory wall or floor G from the effect of the heat in the compartment e' of the heating-chamber and that either of these plates J may be removed when the set of flues H H' has been removed therefrom.

The metallic tube H or H' can be easily removed with or without disturbing the stack or superimposed refractory tiles I I' I², which are attached to the walls or the floor and roof G G', because these tubes are readily accessible.

The operation of the regenerative furnace shown by Figs. 4 to 6, inclusive, is readily understood. When the furnace is in operation, gas is supplied from the pipe O to the combustion-chamber, and the air-blast is forced into the subchamber e from the blast pipe or pipes at the rear end of the furnace. The blast is heated as it passes through the tubes H H', and the hot air is conducted by the side flues O O', which flues O' discharge the heated air into the working chamber A, while the flues O deliver the hot air to the chamber N', from whence the air passes through the ports n' into the combustion-chamber B. The

heated air from the rear end of the working chamber A passes through the passages F F into the middle compartment e' of the chamber E, and it circulates around and in contact with the tile-incased tubes or pipes H H' before it escapes through the exit-passage F' into the stack C, whereby the pipes or tubes H H' are heated to the high temperature necessary to heat the air-blast as it passes through the pipes H H'.

The tiles which incase each pipe or tube H or H' may be made of cylindrical, square, or any other desired form.

I am aware that changes in the form and proportion of parts and in the details of construction of the embodiment of my invention herein shown and described may be made by a skilled mechanic without departing from the spirit or sacrificing the advantages of the invention, and I therefore reserve the right to make such modifications and alterations as fairly fall within the scope of the invention.

Having thus fully described my invention, what I claim as new, and desire to secure by Letters Patent, is—

1. In a furnace, the combination of a heating-chamber, the series of protective tiles extending across said chamber and each stack of tiles extending into the opposite walls thereof, and a metallic tube extending through each stack of tiles and removable therefrom without disturbing said stack, as and for the purposes described.

2. In a furnace, the combination with a heating-chamber, of the interlocking tiles arranged end to end and extending across said heating-chamber, and heating pipes or tubes removably fitted in said series of tiles, substantially as described.

3. In a furnace, the combination with a heating-chamber, of the series of superimposed interlocked tiles extending into the

walls of the chamber, and removable pipes or tubes fitted within each stack of tiles and detachably fastened in place at one end, substantially as described.

4. In a furnace, the combination with a heating-chamber, of plates on the bottom of said chamber, blast-heating tubes or pipes detachably fastened to said plates, and a sectional refractory casing for each tube or pipe, substantially as described.

5. In a furnace, the combination with a heating-chamber having the floor and roof G, G', of a series of plates protected by the floor from the heat in the chamber, sets of blast-heating pipes or tubes extending from the floor to the roof, and each set of pipes fastened detachably to one of said plates, and the interlocking tiles which incase the pipes or tubes and are joined to the floor and roof of said chamber, substantially as and for the purposes described.

6. In a furnace, a divided chamber in the rear wall, having one compartment connected to the furnace-chamber and to the stack or uptake and having a floor G and the roof G' which forms the lower and upper air-chambers e' , e'' , combined with the removable blast-heating pipes or tubes extending across the heating-chamber and secured in the floor and roof thereof to communicate with the air-chambers e' , e'' , and the refractory interlocked tiles which inclose the tubes or pipes and are extending into the floor and roof of said heating-chamber, substantially as and for the purposes described.

In testimony whereof I affix my signature in presence of two witnesses.

WILLIAM STUBBLEBINE.
